CLAIM

The ornamental design for a D.C. power pack or similar article, substantially as shown and described.

DESCRIPTION

FIG. 1 is a front elevational view of a D. C. power pack showing our new design;

FIG. 2 is a side elevational view thereof, the other side being a mirror image;

FIG. 3 is an end elevational view thereof, the other end being a mirror image;

FIG. 4 is a rear elevational view thereof;

FIG. 5 is a front perspective view thereof; and

FIG. 6 is a rear perspective view thereof.
